ROBERT T. CHRISTY, OF NEW YORK, N. Y., ASSIGNOR TO THE KURLASH COMPANY, INC.,
OF ROCHESTER, NEW YORK

DESIGN FOR A HOLDER OR APPLIANCE FOR COSMETICS OR THE LIKE

Application filed January 17, 1931. Serial No. 38,339. Term of patent 14 years.

To all whom it may concern:

Be it known that I, ROBERT T. CHRISTY, a citizen of the United States of America, and a resident of New York city, county of New York, State of New York, have invented a new, original, and ornamental Design for Holder or Appliance for Cosmetics or the like, of which the following is a specification, reference being had to the accompanying drawings, forming part thereof.

In the drawings:

I claim
The ornamental design for a holder or appliance for cosmetics or the like, as shown.

ROBERT T. CHRISTY.
